GUY L. CANNON, OF EAST CLEVELAND, OHIO

VIBRATOR DEVICE

Application filed January 2, 1930. Serial No. 417,903.

In vibrator devices having a piston reciprocated by compressed air, it has heretofore been customary to either mount the device on a slant so that gravity would always leave the piston in a starting position, or a suitably heavy spring was employed for such purpose. In the case of slant mounting, the efficiency of the device is found to be very much diminished, since the direction of thrust is diverted. Furthermore, with such construction, the device must stand at such an awkward position as to be decidedly in the way, and prohibitively so for some usages. In the case of a spring-set piston, other difficulties arise. By reason of the spring bias, the piston stroke is unbalanced, and the efficiency is found to be cut down. Moreover, a spring in such heavy duty position, is subjected to punishment to such extent as to occasion frequent breakage, and consequent delays and repairs. Such springs also weaken and occasionally stick. A vibrator construction eliminating all such difficulties, and making possible a simple and reliable type of construction and operation is accordingly fundamentally important and highly desirable.

To the accomplishment of the foregoing and related ends, the invention, then, consists of the features hereinafter fully described, and particularly pointed out in the claims, the following description and the annexed drawing setting forth in detail certain structure embodying the invention, such being illustrative however of but one of the various ways in which the principle of the invention may be employed.

In said annexed drawing:—

Fig. 1 is a side elevational view of an embodiment of the invention; Fig. 2 is an axial sectional view thereof; and Fig. 3 is a similar view showing the operating parts in another position.

Referring more particularly to the drawing, there is shown a housing 1, which may be of any convenient form with reference to the members to be included, and within such housing a plunger 2 is arranged for reciprocatory motion, the plunger-chamber being closed at its ends by convenient means,

for instance a screw plug 3 with a wrench-hold head, and a screw plug 4 with an opening 5 to receive a connecting bolt for joining the device to a mold plate or other object to receive the vibratory force. In association with the plunger 2 are ports 6 and 7 for communication to the respective ends, and the plunger is desirably provided with circumferential grooves 8, 9, and from these respectively, openings 10, 11 communicate to the space at the ends of the plunger. The circumferential grooves 8, 9, are spaced more closely than the corresponding ports 6, 7, or at least such that only one groove at a time can communicate with the inlet, viz., the groove of the end which has been exhausted. Exhaust ports 12, 13, in the housing are spaced in turn more closely than the grooves 8, 9, or at least such that each will register with a corresponding groove for exhaust at the end of the inward excursion of movement for such groove as carried by the plunger. A supply pipe connection 14 for pressure fluid, most usually air, is arranged in communication to supply the ports.

Means for maintaining the plunger off dead center, so as to insure proper starting, is provided. In the form shown, this comprises a member movable to and fro to control access to the port at one end, and in the detail here, embodies a valve 15 mounted in a bore 16 and backed up by a spring 17, conveniently a coil spring seating about a reduced end of the valve and bearing against a shoulder thereof at one end, and against a backing plate 18 at the other. Such backing plate may conveniently take the form of a washer-like member 19 engageable under the head of the plug 3 and having a lug extension to overlie the spring. The valve 15 has a cutout 20 at its end facing the pressure-fluid supply, such cutout being proportioned to register with port 6 when the valve is in one position, the port however being put in communication with an extension duct or port 21 when the valve is in its other position. A groove 22 or other suitable communicating passageway cooperates with this latter. To maintain the cutout 20 in proper alignment, an aligning or splining slot 23 is provided, and an align-

ing or splining pin 24 therein serves as a control. The pin 24 may conveniently be mounted as a screw 25, thus facilitating ready assembly and disassembly.

5 The manner of operation of the device will be readily understood from the foregoing. Being connected to an object to be operated upon, for instance the plate of a molding machine in foundry usage, or a portion of a concrete form in cement-molding usage or the like, pressure fluid, usually air for instance at a pressure of about 70-80 pounds per square inch, is admitted by the control of a master valve in the pipe 14. The spring 17 normally 10 maintains the valve 15 in a position to block communication to the port 6, and as long as the pressure is shut off in the pipe 14, the ports will be at rest in the position shown in Fig. 3. But when now the master valve 15 in the pipe is opened to allow the fluid to enter, the port 7 being blocked by the piston 2, the back-lash of pressure momentarily 15 forces the valve 15 back against the spring 17 to its position shown in Fig. 2. At this instant the plunger 2 happens to still be in the dotted line position shown in Fig. 2, the opening 10 of the plunger being in line with port 6, and thus the pressure fluid takes the path through port 6 and opening 10 and out 20 to the left hand end of the plunger 2. Immediately the plunger is forced over to the right or its full line position shown in Fig. 2, and on the movement of the groove 8, communication with the port 6 is first cut off and 25 then communication with the exhaust port 12 is opened, thereby exhausting the charge of fluid from that end of the plunger chamber. Meanwhile, the spring 17 has thrown the valve 15 back to the right. Pressure fluid 30 now enters port 7 and the groove 9 as it comes into registry, and thence proceeds through the opening 11 to the right hand end of the plunger. The left end of the plunger being exhausted, the pressure fluid at the right 35 throws the plunger back to the left, and the moving groove 9 first cuts off the inlet port 7 and then exhausts through port 13. Port 6 is put in communication with opening 10, and 40 since the valve 15 sets with the groove 22 and passway 21 aligned, final exhaust of the left end of the plunger 2 is insured, and a cycle is completed. It will be observed also that 45 when the pressure-fluid is shut-off in pipe 14, since the spring 17 biases the valve 15 into position with the groove 22 aligned with auxiliary passway or vent 21, dead-centering of the plunger 2 is prevented, and relief or exhaust of the left end of the plunger through the feed port 6 leaves the plunger uniformly 50 in the position shown in Fig. 3, ready for a reoccurrence of the cycle starting with the forcing valve 15 back, and so on, as above set forth. Cyclic movement, and rapid reciprocation of the plunger 2 is thus had, the particular effects being gauged by the propor-

tions, and by the pressures employed; in molding machine practice for instance a vibratory rate of around four thousand per minute being ordinarily desirable. Simplicity and durability, in addition to positiveness of action are furthermore had, as seen. When the master valve in the pipe 14 is shut off, the valve 15 always insures a relief through inlet port 6 to provide final positioning of the parts as shown in Fig. 3, and the device is always ready for starting; with entire elimination of difficulties from dead-centering, etc., and without imbalance.

55 By reason of the uniform action at both ends of the plunger, highly efficient application of power is had, so that small units develop a surprisingly large amount of power.

60 Other modes of applying the principle of the invention may be employed, change being made as regards the details described, provided the means stated in any of the following claims, or the equivalent of such, be employed.

I therefore particularly point out and distinctly claim as my invention:—

65 1. A fluid motor, comprising a housing, a plunger reciprocable therein, ports for supplying pressure fluid to each end of the plunger, an inlet communicating with said ports, an exhaust-vent communicable with one such supply-port, a member in relation with said exhaust-vent and said last-named supply-port held by fluid-pressure when the line-pressure is on whereby to open the inlet to said supply-port and close the vent, and resilient means to move said member when the line-pressure is off whereby to close the inlet to said supply-port and open the vent.

70 2. A fluid motor, comprising a housing, a plunger reciprocable therein, ports for supply of pressure fluid to each end of the plunger, an inlet communicating with said ports, an exhaust-vent aligned with one such supply-port, a member in relation with the said exhaust-vent and said last-named supply-port held by fluid-pressure when the line-pressure is on whereby to open the inlet to said supply-port and close the vent, and resilient means to move said member when the line-pressure is off whereby to close the inlet to said supply-port and open the vent.

75 3. A fluid motor, comprising a housing, a plunger reciprocable therein, ports for supplying pressure fluid to each end of the plunger, discharge ports for exhaust after each respective stroke of said plunger, a valve guarding one such supply port, said valve having a cutout to allow entry of pressure fluid when in retracted position and a groove to allow exit of exhaust fluid when in advanced position, an auxiliary vent with which such groove may register when the valve is in advanced position, and resilient means for urging said valve to advanced position.

80 4. A fluid motor, comprising a housing, a

- plunger reciprocable therein, ports for supplying pressure fluid to each end of the plunger, discharge ports for exhaust after each respective stroke of said plunger, a valve 5 guarding one such supply port, said valve having a cutout to allow entry of pressure fluid when in retracted position and a groove to allow exit of exhaust fluid when in advanced position, an auxiliary vent with which 10 such groove may register when the valve is in advanced position, an aligning slot in said valve, an aligning pin controlling said slot, and resilient means for urging said valve to advanced position.
- 15 5. A fluid motor, comprising a housing, means for connecting said housing to a plate to be vibrated, a plunger reciprocable in said housing, ports for supplying pressure fluid to each end of the plunger, said plunger having 20 circumferential grooves each alternately registerable with one of such ports and openings from each groove to the corresponding end of the plunger, a pair of exhaust ports in the housing each registerable alternately with 25 one of such grooves, a valve guarding the pressure fluid entry port for one end of said plunger, said valve having a cutout to allow entry of pressure fluid when in retracted position and a groove to allow exit of exhaust 30 fluid when in advanced position, an auxiliary vent with which said groove may register when the valve is in advanced position, and resilient means for urging said valve to advanced position.
- 35 6. A valve construction for a fluid motor, comprising a housing, a reciprocable valve member mounted therein, and resilient means normally holding said member at one end of its stroke, aligned ports located diametrically 40 of said member in the housing, and a feed inlet at the end of said valve member, said valve member when at the aforementioned end of the stroke blocking communication between the feed and one of said ports, while 45 establishing communication between such laterally aligned ports.
7. In a valve construction for fluid motors, a housing, a reciprocable valve member mounted therein, aligned ports located diametrically of said member in the housing, and a feed opening at the end of said valve member, said member having a cutout at the end to establish connection between the feed opening and one of said ports when in one position, said member having also a groove for communicating with the diametrically aligned ports when in another position, and means for preventing rotary motion of said member, said means including a splining slot in 55 the member and a coacting screw-adjusted pin in the housing.
- 60 Signed by me this 28th day of December, 1929.

GUY L. CANNON.
